UNITED STATES PATENT OFFICE

HELEN V. HOLMES, OF CHICAGO, ILLINOIS.

DESIGN FOR A FLAG-HOLDER.

SPECIFICATION forming part of Design No. 22,128, dated January 10, 1893.

Application filed October 20, 1892. Serial No. 449,531. Term of patent 3½ years.

To all whom it may concern:

Be it known that I, HELEN V. HOLMES, a citizen of Chicago, residing at 3,033 Vernon avenue, in the county of Cook and State of Illinois, have invented certain new and useful Improvements in a new and original Design for a Flag-Holder, of which the following is a specification, reference being had to the accompanying drawing, which represents a front elevation of a flag-holder illustrating my design.

The leading feature of the design resides in a hemispherical body on which is mounted a figure; the body being perforated to receive the flag staffs of flags of different nations. The hemispherical body is provided with a series of perforations arranged in tiers as shown, so as to permit the insertion of the ends of staffs

or rods of different sizes upon which may be hung the flags of nations or any desired arrangement of banners, symbols or the like, adapted to give the desired pleasing effect. The body is supported upon a base or platform as shown, and upon its apex is mounted a figure of a person standing erect and grasping the handle of a sword or dagger with one hand while holding aloft a flag or banner with the other.

What I claim is:—

The design for a flag holder &c., substantially as shown and described.

HELEN V. HOLMES.
